(57) **CLAIM**

The ornamental design for a retractable cleat, substantially as shown and described.

DESCRIPTION

FIG. 1 is a perspective view of a retractable cleat embodying my design;

FIG. 2 is a front elevational view of the cleat shown in FIG. 1.

FIG. 3 is a side elevational view of the cleat shown in FIG. 1.

FIG. 4 is a top plan view of the cleat shown in FIG. 1.

FIG. 5 is a bottom plan view of the cleat shown in FIG. 1.

FIG. 6 is a front elevational view of the cleat shown in FIG. 1 in the extended condition.

FIG. 7 is a side elevational view of the cleat shown in FIG. 1 in the extended condition; and,

FIG. 8 is an exploded view of the cleat shown in FIG. 1.
